UNITED STATES PATENT OFFICE.

HERBERT CRIPPEN, OF ROCHESTER, NEW YORK.

SAFETY APPLIANCE FOR STEAM-BOILERS.

No. 866,265.

Specification of Letters Patent.

Patented Sept. 17, 1907.

Application filed July 17, 1903. Serial No. 166,032.

To all whom it may concern:

Be it known that I, HERBERT CRIPPEN, of Rochester, in the county of Monroe and State of New York, have invented certain new and useful Improvements in Safety Appliances for Steam-Boilers; and I do hereby declare the following to be a full, clear, and exact description of the same, reference being had to the accompanying drawings, forming a part of this specification, and to the reference numerals marked thereon.

10 My present invention relates to safety appliances for steam boilers and more especially to that class of such devices particularly applicable to boilers employing a liquid or gaseous fuel; and it is the object of my invention to produce an appliance of this character whereby the supply of fuel will be automatically interrupted or cut off should the water level within the boiler reach a predetermined stage, and also to provide means whereby the device may be reset to restore the fuel supply so that the service of the boiler may be 15 uninterrupted pending the readjustment of the parts of the appliance.

Other features of novelty and advantage will be hereinafter more fully described and pointed out in the claims hereunto appended.

20 In the drawings: Figure 1 is a central vertical sectional view of a steam boiler, provided with a safety device embodying my said invention. Fig. 2 is a central vertical sectional view taken longitudinally through the device, showing the parts in the normal position, and Fig. 3 is a similar view showing the position of the parts after operation.

Similar reference numerals in the three figures indicate similar parts.

In the present embodiment of my invention 1 designates the shell of a steam boiler of any suitable type, beneath which is located any suitable form of burner

2. Passing directly over this burner, and entering the crown sheet of the boiler, is a pipe 3, the upwardly extending portion 4 thereof being connected to the 30 pipe 3, within or above the crown sheet of the boiler. The length of this pipe 4 may be varied under different conditions, but in all cases will be of a length equal to the height of the extreme low water level, or the lowest level at which it is safe to run the boiler.

40 Upon the opposite end of the pipe 3 outside the burner 2 is a fitting or casting 5, provided with an aperture 6 within which is threaded or otherwise secured the pipe 7, connected through the elbow 8, and nipple 9 to the pipe 10, passing through the boiler shell and 45 provided with an upturned portion 11 terminating at substantially the same height as the upwardly extending pipe 4. Should such a construction be adopted a coupling 12 should be employed for convenience in fitting the parts.

55 In the fitting or casting 5 below the pipe 7 is provided an aperture 13 through which communication

with the atmosphere is controlled by the screw threaded plug 14, provided with the passage 15.

A screw threaded aperture is provided in the fitting or casting 5, substantially in alignment with the pipe 60 3, and into this aperture is fitted the plug 17, carrying the tube or sleeve 18, of a reduced size, and extending into the pipe 3, until the end thereof rests above the burner. Fitted within this tube 18, and extending through the plug 17 is a rod 19, preferably provided 65 upon one end with the corrugations 20. This rod 19 normally occupies the position shown in Fig. 2, and is retained from operation by the fuse 21, interposed between the end of said rod 19 and the tube 18 and is composed of any suitable alloy or other material melting at a comparatively low temperature. As the rod 19 passes through the plug 17, a stuffing-box 22 is provided to form a tight joint. At the extremity of this rod 19 is formed one of the members 23 of a connecting 70 joint, screw-threads or other suitable means being employed in securing the same to said rod.

Extending laterally from the casting 5 are a pair of diametrically disposed lugs 24—24 provided with recesses 25—25. Into these recesses 25—25 are adapted to rest the extremities of the arms 26—26 of the frame 80 27. Mounted longitudinally of this frame 27 is a valve stem 28 carrying at one end the connecting member 29 connected to the corresponding member 23 by the removable screw or pin 30, to form a joint. Adjacent this member 29 the valve stem 28 is screw-threaded, 85 as at 31, and over these threads is fitted the thumb nut 32 normally occupying the position indicated in full lines in Fig. 2. Adjacent this thumb screw 32 is an abutment 33, through which the stem 28 is slidingly fitted. Upon one side of this abutment is provided a 90 seat 33^a for the thumb-screw 32, and upon the opposite side thereof is provided a spring seat 34.

Upon the valve stem 28 is provided a stop 35 against which abuts the spring seat 36. Between the spring seat 36 and the spring seat 34 the helical compression 95 spring 37 is interposed, the normal tendency of this spring being to move said rod 19 and the stem 28 to the left. However, the fusible connection 20 between the tube 18 and the rod 19 normally retains the parts in the position shown in Fig. 2.

Upon the end of the valve stem 28 is screw-threaded or otherwise secured the needle valve plug 38 provided with a valve seat 39 adapted to register with the valve seat 40 in the casting 41 to form a cut-off for the fuel supply. This casting 41 is provided with an externally-screw-threaded extension 42, screw-threaded into the end of the frame 27, in alignment with the valve stem 28. This extension 42 is formed hollow and into this hollow portion may be fitted the guide or support 43 for the valve stem 28. A stuffing-box gland 110 44 is also fitted within this hollow extension, being held in position by the cap nut 45 screw-threaded upon

the extension 42, to form a tight joint through which the valve stem 28 may slide.

Leading from the valve seat 40 in the casting 41, is formed a passage 46, passing through the extension 47 of the casting, said extension being externally screw-threaded, over which is fitted the nut 48, carrying the coupling piece 49 secured to the pipe 50 connected to a reservoir or other source of fuel supply.

Perforating the casting 41 above the valve seat 40 is 10 provided a passage 51 leading through the extension 52, said extension being also provided with any suitable form of coupling, such as 53 and 54, connected to the pipe 55, leading to the vaporizing retort 56 and burner 2, both of which may be of any suitable type.

15 In proximity to the thumb-screw 32 is a stop of any suitable construction, said stop in the present embodiment consisting of a thumb screw 57 provided with a screw-threaded stem 58 passing through the frame 27 and engaging the thumb nut 32 to prevent rotation of 20 said nut upon the stem 28, when said parts are in the position shown in Fig. 2.

Under ordinary conditions evaporation of water within the boiler will normally take place from a level in proximity to the dotted line, Fig. 1. Under these 25 conditions a constant circulation of water will be maintained through the pipes 10, 7, fitting or casting 5 and pipe 3, entering the pipe 10 from the boiler, passing around the elbow 8 and down the pipe 7, through the casting 5 between the tube 18 and the pipe 3 and back 30 into the boiler through the extension 4. This circulation is set up and maintained by the superheated water in the pipe 3, located directly above the burner, rising, causing water at a comparatively lower temperature to pass down into the inlet pipe 10. Under normal 35 conditions this circulation will continue. However, should the water level fall to the level of the tops of the inlet and outlet pipes 10 and 4 respectively, it will be obvious that the circulation of water through said pipes will be interrupted, and the water remaining in the 40 pipe will be quickly evaporated or dispelled by the heat of the burner directly beneath. Heretofore the fuse 21 will be protected by the water passing through the pipe 3, the temperature of which is considerably below the fusing point of the fuse. However, when 45 the water has been dispelled from said pipe 3, the temperature thereof will rapidly rise, and communicating its heat to the fuse 21, will melt the same, breaking the connection between said tube 18 and the rod 19, releasing the said rod. As the valve stem 28, under tension of the spring is connected to, and normally retained in operative position by the rod 19, it will now be released, and acting under the influence of the spring 37 will be thrust to the left causing the needle valve 38 to seat itself upon the valve seat 40, closing communication 50 between the supply pipe 50 and the pipe 55 leading to the burner and consequently causing the burner to be extinguished. Thus it will be seen that the source of heat is removed when the water level falls to such a degree as to endanger the crown sheet, 55 tubes or other parts of the boiler through overheating, and to eliminate danger from all possible sources, such as the sudden entrance of feed water under such conditions. As the source of heat is removed from the boiler, the same will now rapidly cool, and the water 60 level may then be restored to its normal working level.

In order that the service of the boiler may be continued pending the renewal of the fuse, a thumb-screw 32 is provided upon the screw-threaded portion 31 of the stem 28, which may be rotated after the set screw 57 has been retracted, to cause the cut off or needle valve 70 to reestablish communication between the supply pipe 50 and the pipe 55 leading to the burner.

In order to renew the fusible connection 21, the pin or screw 30 connecting the rod 19 and the valve stem 28 is removed and the plug 17 is unscrewed from the 75 casting or fitting 5, when the rod 19 and the tube 18 will both be accessible. After the fuse connection between the end of the rod 19 and the tube 18 has been renewed, said plug may be replaced in the casting 5, and the parts restored to the position shown in Fig. 2, when the 80 needle valve 38 will be held open and the device will be again in its operative position.

The valve plug 14 is provided for draining or blowing off the pipes 3 and 7, to remove sediment or to withdraw the water therefrom after blowing off the boiler. 85

While I have illustrated and described certain pipe connections and fittings in the present embodiment, it will of course be understood that any suitable connections may be employed as desired.

It will also be understood that I do not limit myself 90 to the details of construction herein shown and described, as many modifications and changes might be made, which modifications and changes could be made without departing from the spirit of my invention.

I claim as my invention—

1. The combination with a steam boiler, a water chamber communicating with the water space of said boiler and a burner having a fuel supply, of a part projecting into said water chamber, a cut-off for the fuel supply including a valve and a stem therefor also projecting 100 into the chamber, and a fusible connection between the valve stem and the projecting part for normally retaining the valve in open position.

2. The combination with a steam boiler, a burner therefor having a fuel supply connected thereto and a water chamber exposed to the heat of the burner, of a cut-off valve for the fuel supply having its valve stem provided with a detachable part projecting into the water chamber of the boiler, a sleeve also projecting into the water space of the boiler adjacent to the stem, a thermally controlled device normally connecting the said stem and sleeve, and a detachable part containing the sleeve and the detachable part of the stem.

3. The combination with a steam boiler, a burner therefor having a fuel supply connected thereto, and a water chamber communicating with the water space of the boiler and exposed to the heat of the burner, of a cut-off valve for controlling the fuel supply located exteriorly of the boiler and having a stem with a part extending into the water chamber thereof, a sleeve inclosing said stem, and a fusible substance normally sealing the bore of the sleeve and serving as a connection between the sleeve and stem.

4. The combination with a steam boiler, a burner therefor having a fuel supply connected thereto, of a fitting on the boiler, a cut-off valve for the fuel supply having a stem with a part extending through the fitting into the water space of the boiler, means normally tending to operate the stem, a sleeve secured to the fitting and surrounding the stem, and a fusible substance normally sealing the bore of the sleeve and serving as a connection between the sleeve and stem.

5. The combination with a steam boiler, and a burner therefor having a fuel supply connected thereto, of a hollow fitting secured to the boiler and communicating with the water space thereof, a plug detachable from the fitting and carrying relatively fixed and movable members, a thermally-controlled connection between said members,

- and a valve in the fuel supply controlled in its operation by said movable member.
6. The combination with a steam boiler, and a burner therefor having a fuel supply connected thereto, of a fitting having portions communicating with the boiler and exposed to the heat of the burner, a plug detachable from the fitting and carrying relatively stationary and movable members, a thermally-controlled connection between the said members for normally preventing their relative movement, and a valve for the fuel supply having its stem connected to said movable member. 85
7. The combination with a boiler, and a burner therefor having a fuel supply connected thereto, of a fitting having portions communicating with the boiler and exposed to the heat of the burner, a plug having a sleeve thereon projecting into the fitting, a stem inclosed by the sleeve and extending through the plug to the exterior of the fitting, a valve for the fuel supply having a part controlled by the said stem, and a thermally-controlled connection for normally preventing relative movement of the stem and sleeve. 90
8. The combination with a boiler, and a burner therefor having a fuel supply connected thereto, of a fitting having portions communicating with the boiler and exposed to the heat of the burner, a plug detachable from the fitting having a sleeve fixed therein and projecting into the fitting, a relatively movable stem surrounded by the sleeve and extending loosely through the plug, a fusible connection between the sleeve and stem for normally preventing relative movement between them, and a valve for the fuel supply controlled by the said stem. 95
9. The combination with a boiler, and a burner therefor having a fuel supply connected thereto, of a hollow fitting, pipes connected at their outer ends by said fitting and having their opposite ends extending vertically to a given level within the boiler, one of said pipes being exposed to the heat of the burner, a thermally-controlled device arranged with one of said pipes, and a valve for the fuel supply controlled in its operation by said thermally-controlled device. 100
10. The combination with a steam boiler and a burner having a fuel supply connected thereto, of a water chamber connected to said boiler and exposed to the heat of the burner, a cut-off interposed between said fuel supply and burner, a releasing device to permit the closing of said cut-off during the absence of water in said chamber, and means for reopening said cut-off independently of the releasing device. 105
11. The combination with a steam boiler and a burner having a fuel supply connected thereto, of a water circulating pipe connected to said boiler and exposed to the heat of the burner, a cut-off interposed between said fuel supply and burner, a spring operating to close said cut-off, a releasing device to permit the closing of said cut-off upon the interruption of circulation through said pipe, and means for overcoming the action of said spring and reopening said cut-off. 110
12. The combination with a boiler, and a burner therefor having a fuel supply connected thereto, of a hollow fitting having communication with the boiler and provided with laterally-arranged lugs thereon, a thermally-controlled device carried by said fitting and having an operating part extending to the exterior of the latter, a frame having arms adapted to co-operate with said lugs on the fitting, a valve for the fuel supply, and a valve stem guided in said frame and connected to the operating part of the thermally-controlled device. 115
13. The combination with a boiler, and a burner therefor having a fuel supply connected thereto, of a hollow fitting having communication with the boiler and provided with a part exposed to the heat of the burner, a rod extending into the fitting, a thermally-controlled device for normally preventing movement of the rod, a valve for the fuel supply, a stem for operating the valve having a detachable connection with the said rod, and a frame serving to guide the said stem and as a connection between the valve and fitting. 120
14. The combination with a steam boiler, and a burner therefor having a fuel supply connected thereto, of a water chamber exposed to the heat of said burner and communicating with the water space of the boiler, a cut-off located in the fuel supply having a relatively movable operating portion extending into the water chamber and a fuse located in said chamber connected to said operating portion to normally restrain its operation. 125
15. In combination with a steam boiler and a burner therefor having a fuel supply connected thereto, of a water chamber communicating with the water space of the boiler, a cut-off located in the fuel supply having a relatively movable operating member, and removable plug fitted in the water chamber having a relatively fixed projection extending into the water chamber, a relatively movable portion extending into said chamber and connected to the operating member of the cut-off and a fusible substance located within the water chamber and connecting said projection and movable portion. 130
16. In combination with a steam boiler, a burner therefor having a fuel supply connected thereto, and a water chamber communicating with the water space of the boiler, of a cut-off located in the fuel supply, a relatively movable operating member therefor, a plug removably fitted in said water chamber having a hollow portion projecting therein, a longitudinally movable portion located within said hollow portion and connecting with the operating portion of the cut-off, and a fusible connection with the said chamber and normally connecting said hollow and movable portions. 135
17. In combination with a steam boiler, a burner therefor having a fuel supply connected thereto, and a water chamber communicating with the water space of the boiler, of a cut-off located in the fuel supply having a relatively movable operating member, means normally acting thereon to close the cut-off, and a plug removably fitted in the water chamber having a hollow portion projecting therein, a longitudinally movable portion mounted in said hollow portion and connected to said operating member, and a fusible connection between said hollow and movable portions normally serving to retain the latter in relatively fixed relation. 140
18. The combination with a steam boiler, a burner therefor having a fuel supply connected thereto and a water chamber communicating with the water space of the boiler, of a valve located in the fuel supply having a movable operating member, means normally acting thereon to close the valve, a plug removably fitted into the water chamber having a tubular extension thereon, a rod movable longitudinally within said extension and connected to the operating member of the cut-off and a thermally controlled device for normally retaining the rod and operating member in their retracted positions. 145
19. The combination with a steam boiler, and a burner therefor having a fuel supply connected thereto, of a water circulating chamber extending through the combustion chamber of the burner and communicating at different points with the water chamber of the boiler, a cut-off located in the fuel supply having an operating member, and a fuse controlled by the temperature within said chamber for controlling the operation of the valve operating member. 150
20. The combination with a steam boiler, and a burner therefor having a fuel supply connected thereto, of a water circulating pipe extending above the burner and communicating at both ends with the water space of the boiler, a cut-off in the fuel supply having a valve stem extending into said pipe and normally operating to close the cut-off and means controlled by the temperature within the said pipe and connected directly to the valve stem for retaining the stem in its retracted position. 155
21. The combination with a steam boiler, a burner therefor having a fuel supply connected thereto, and a water chamber communicating with the water space of the boiler and exposed to the heat of the burner, of a cut-off valve located in the fuel supply, a longitudinally movable valve stem for operating the latter, a relatively fixed tubular extension projecting into the water chamber, a longitudinally movable rod mounted within the tubular extension and movable with the valve stem, and means controlled by the temperature within the chamber for normally retaining said rod and extension in fixed relation. 160
22. In a safety appliance, the combination with a

steam boiler, and a burner having a fuel supply connected thereto, of circulating pipes extending through the combustion chamber of the burner and having their apertures located at a predetermined height within said boiler, a fitting connecting said pipes through which water from said boiler normally circulates, a stationary member located in one of said pipes, a movable member, a fusible connection between said members, and a controlling device connected to said fuel supply, and adapted to be released by said movable member to interrupt the fuel supply after the circulation through said pipes ceases.

23. In a safety appliance, the combination with a steam boiler, and a burner and fuel supply connected thereto, of circulating pipes exposed to the heat of the burner and having their apertures located at a predetermined height within said boiler, a fitting connecting said pipes through which water from said boiler normally circulates, a plug carrying a stationary and a movable member fitted in said fitting, a fusible connection between said members, and a controlling device connected to said fuel supply, and adapted to be released by said movable member to interrupt the fuel supply after the circulation through said pipe ceases.

24. In a safety appliance, the combination with a steam boiler, and a burner having a fuel supply connected thereto, of circulating pipes exposed to the heat of the burner and having their apertures located at a predetermined height within said boiler, a fitting connecting said pipes through which water from said boiler normally circulates, a stationary member located in one of said pipes, a movable member, a fusible connection between said members, and a controlling device connected to said fuel supply, a valve stem for operating said device adapted to be released by said movable member to interrupt the fuel supply after the circulation through said pipes ceases, and a retracting device operating upon said stem for restoring the fuel supply.

25. In a safety appliance, the combination with a steam boiler, and a burner having a fuel supply connected thereto, of circulating pipes exposed to the heat of the burner and having their apertures located at a predetermined height within said boiler, a fitting connecting said pipes through which water from said boiler normally circulates, a plug carrying a stationary and a movable member fitted in said fitting, a fusible connection between said members,

and a controlling device connected to said fuel supply, and adapted to be released by said movable member to interrupt the fuel supply after the circulation through said pipes ceases and a retracting device for said controlling device to restore said fuel supply.

50

26. The combination with a steam boiler, a burner therefor and a fuel supply connected thereto, of a water chamber communicating with the water space of the boiler, a frame connected thereto having a cut-off valve at one end thereof connected in the fuel supply, a valve stem movable longitudinally of the frame for operating the cut-off, a spring interposed between the frame and the stem for operating the latter, an extension connected to said stem and extending into said water chamber a relatively fixed member projecting into said water chamber, and means controlled by the temperature of the water chamber for normally connecting said extension and fixed member and thereby retaining the valve stem retracted.

55

27. The combination with a steam boiler, a burner therefor having a fuel supply connected thereto, and a water chamber communicating with the water space of the boiler, of a cut-off valve located in the fuel supply having an operating stem, a spring for operating said stem to close its valve, and a plug removably fitted into the water chamber having a tubular extension thereon, an extension connected to said stem and movable longitudinally within the tubular extension, and a fusible substance connecting said extensions.

60

28. The combination with a boiler, a burner therefor having a source of fluid fuel supply connected thereto, and a cut-off in the fuel supply having an operating stem and means normally operating thereon to close the cut-off, of a water chamber communicating with the water space of the boiler, a tubular extension projecting into the water chamber and having the valve stem movable longitudinally therein, and a fusible substance sealing the tubular extension and forming a connection between the tubular extension and valve stem to prevent operation of the latter while the temperature in the water chamber is normal.
